BOAT JOINT CONSTRUCTION

Filed Aug. 2, 1930

UNITED STATES PATENT OFFICE

CLAUDE H. ROGERS, OF PETERBORO, ONTARIO, CANADA

BOAT JOINT CONSTRUCTION

Application filed August 2, 1930. Serial No. 472,523.

The principal objects of this invention are to render the longitudinal joints of the planking in boats thoroughly water-tight and to accomplish the desired result in a simple, economical and very effective manner, thereby producing a boat construction of very dependable quality, which will withstand the effects of rough handling and the vibration of motors installed in the boat.

10 The principal features of the invention consist in compressing the fibres of the wood in the angles of the meeting faces of a lapped joint and utilizing the expansion of these compressed fibres upon becoming wet or 15 absorbing moisture to effectively seal the joint against the ingress of water therethrough.

A further important feature consists in the novel arrangement of an additional packing 20 in the joint.

A further and very important feature of the invention consists in the simple method of constructing the joint and placing the packing therein.

25 In the drawings, Figure 1 is a plan view of the simple mechanism for forming my improved joint.

Figure 2 is an enlarged cross section through the line 2—2 of Figure 1.

30 Figure 3 is an enlarged sectional detail showing the compressing disc in operation.

Figure 4 is an enlarged sectional detail showing the cord placing disc in operation.

35 Figure 5 is a much enlarged sectional view showing the manner of placing the cord in the compressed groove in the wood fibres.

Figure 6 is an enlarged detail showing a modified method of making a joint.

Figure 7 is a sectional view of a plank completed after being treated as in Figure 6.

40 Figure 8 is a sectional view of the plank shown in Figure 7, illustrating the manner in which the fibres expand to form a water-tight joint.

45 Figure 9 is a sectional perspective detail of

a portion of a boat hull constructed in accordance with this invention.

It has been quite common for a number of years in the boat building art to form the planking of long narrow strips having each edge cut away in what is known as a "ship-lap." These strips are lapped one over the other and they are nailed to be cross ribbed.

This form of joint is a fairly good one but it is desirable to make a perfect seal at the angles between the meeting faces of the lapped joint and to accomplish this result I have devised a very simple, though very effective method of manufacture.

The strips when formed with their lapped edges are placed upon a table 1 and one lapped edge is pressed against a longitudinal guide 2 by means of a shoe 3 which is pivotally mounted on a pin 4 secured in the table.

A lever 5 pivotally mounted on a pivot bolt 6 secured to the table has the end 7 pressing against the back of the shoe 3 and tension is applied to the lever by means of a cord 8 and weight 9, which extends over a pulley 10.

70 A bracket 11 is secured to the table with its top edge flush with the table top and it has mounted thereon a block 12 which is slotted longitudinally on its inward side and a pair of rollers 13 and 14 are arranged in said slots and mounted in fixed bearings 75.

The roller 13 is preferably formed with a V-edge which presses into the fibres of the wood in the angle of the meeting faces of the lap and forms a narrow groove therein by compressing the fibres.

80 The roller 14 is provided with a concaved edge which follows over the compressed corner in the wood strip and acts to guide a strip of fibrous material such as a piece of cord into the groove. The cord is pressed into the groove formed by the roller 13 before the fibres recover from the pressure applied thereby and a partial recovery of the 85

90

fibres causes them to pinch and hold the fibrous cord or strip placed therein.

When the cord has thus been placed it is held securely so that the strips may be handled with ease without danger of the cord becoming displaced.

Varnish is applied to the edges of the strips as they are placed together in constructing the boat and the cords are thus sealed tight.

- 10 At any place where the joint has a tendency to leak the water first has access to the grain of the wood and the cord strip and the wood which has been compressed swells and presses outwardly, pressing the cord against the adjoining surface of the adjacent wood strip.

The cord and the expanded wood thus cooperate to make a thoroughly water-tight joint and as such joint occurs twice in each lapped pair of strips it will be realized that 20 the joint will be made very secure against the ingress of water.

The result desired may be acquired for certain types of boats without the use of the cord. In such cases a roller 15 formed with 25 a more or less squared flange 16 compresses the wood at the angle of the joint forming a groove 17. After passing the roller 15, the edge 18 at one side of the groove is partly cut away, leaving the groove quite shallow but 30 the wood which has been compressed when subject to moisture will swell and form a projection as shown at 19 in Figure 8. This swelling of the wood is very effective in sealing the joints where the boat is not subject 35 to too much vibration.

The bracket 11 is provided with a flange 19 on its outer side in which set screws 20 are threaded. These set screws bear against the block 12 and enable the adjustment of the 40 rollers in relation to the guide to regulate the depth of the compressed groove formed in the wood fibres.

A boat hull when constructed of wood strips manufactured in the manner described 45 will be extremely safe and ensures the boat from any possible leakage at the joints.

What I claim as my invention is:

1. A method of forming water-tight joints in wood strips, consisting in forming the 50 adjoining edges of the wood strips with interfitting tongue and groove formations, and deforming the material at the bottom of the groove of one member to co-operate with the tongue of the adjoining strip forming a self-sealing joint.

2. A method of forming water-tight joints in wood strips, consisting in forming the wood strips with lapped edges, compressing the fibres of the wood in the angles of the 60 lap, inserting a fibrous strip into the compressed portion to seal against the lapped edge portion of the mating strip, and securing the wood strips together.

3. In a method of jointing wood strips 65 in water-tight joints, the steps of running

the wood strips longitudinally in pressure contact with a roller to compress a narrow strip of the fibre and directing a cord under a second roller into the groove formed by the depression of the fibres.

4. A method of forming water-tight joints in wood strips, consisting in forming the adjoining edges of the wood strips with interfitting tongue and groove formations, deforming the wall of the groove of one member in alignment with the interfitting tongue of the other member, then embedding a strip of sealing material in the deformation of the groove wall to seal against the tongue portion of the other member.

5. A method of forming water-tight joints in wood strips, consisting in forming the adjoining edges of the wood strips with interfitting tongue and groove formations, deforming the wall of the groove of one member in alignment with the interfitting tongue of the other member, then laying a length of 85 corded fibrous material in the deformation of the groove wall to form a seal against the interfitting tongue of the other member.

6. A method of forming water-tight joints in wood strips, consisting in forming the adjoining edges of the wood strips with interfitting tongue and groove formations, depressing the fibres of the groove wall for a 95 portion of its width, and cutting away the adjacent non-depressed portion of the groove wall forming a self-sealing joint.

7. In a method of forming water-tight joints between fibrous strips, the steps of 100 compressing longitudinally the side edge of one strip to form a groove and laying a length of corded fibrous material in the longitudinal groove so formed utilizing the expansive effort of the compressed portion to 105 displace the corded fibrous material outwardly in pressure sealing engagement with the surface of the opposing strip.

8. A construction unit comprising a wood strip having a length of cord embedded in 110 a groove extending longitudinally of the edge thereof said groove being formed by compressing the fibres of the strip whereby the expansive effort of the compressed fibres tends to displace the embedded cord outwardly.

9. A construction unit comprising a wood strip having a mating groove in the edge, the fibres of the mating groove wall being 120 depressed in part to form a second longitudinal groove, and a length of cord embedded in said second groove.

10. In a boat joint construction, wood strips formed with lapped edges and having the wood at the inside angle of the lap compressed in a continuous longitudinal strip capable of swelling outwardly under the effect of moisture to effect a sealed joint with the lapped edge portion of the mating wood strip.

11. A construction unit comprising a wood strip having an angular mating groove extending longitudinally of the edge, and a length of cord embedded in the groove wall 5 at the angle.
12. A construction unit comprising a wood strip having a longitudinal mating groove formed in the edge presenting angularly related groove walls, and a length of cord embedded in one of said groove walls adjacent their meeting angle.
